Primary Examiner — Vy N Koenig**CLAIM**

The ornamental design for a hexagonal product packaging, as shown and described.

DESCRIPTION

FIG. 1 is an exploded perspective view of a hexagonal product packaging showing the new design;

FIG. 2 is a perspective view of the packaging of FIG. 1 in a closed configuration;

FIG. 3 is a first side view thereof, the opposite side being a mirror image thereof;

FIG. 4 is a second side view thereof, the opposite side being a mirror image thereof;

FIG. 5 is a top view thereof; and,

FIG. 6 is a bottom view thereof.

The solid jagged lines running horizontally through the lid and body of the packaging depict jagged cuts in the package that form part of the claimed design.
